UNITED STATES PATENT OFFICE.

WALTER ROYAL KIRK, OF BOSTON, MASSACHUSETTS.

DESIGN FOR A BOWLING SCORE-BOARD.

44,066.

Specification for Design.

Patented May 20, 1913.

Application filed November 22, 1912. Serial No. 732,912. Term of patent 7 years.

To all whom it may concern:

Be it known that I, WALTER ROYAL KIRK, a citizen of the United States, residing at Boston, in the county of Suffolk and State of Massachusetts, have invented a new, original, and ornamental Design for a Bowling Score-Board, of which the following is a specification, reference being had to the accompanying drawing, forming part thereof.

The figure is a plan view of a bowling score board, showing my new design.

I claim:

The ornamental design of a bowling score board, as shown.

WALTER ROYAL KIRK.

Witnesses:

HORACE W. SEXTON,
HERMAN A. MINTZ.
